(57) **CLAIM**

The ornamental design for a writing instrument, as shown and described.

DESCRIPTION

FIG. 1 is a perspective view of a writing instrument according to the present design;

FIG. 2 is a front view of the writing instrument of FIG. 1; FIG. 3 is a rear view of the writing instrument of FIG. 1; FIG. 4 is a right side view of the writing instrument of FIG. 1;

FIG. 5 is a left side view of the writing instrument of FIG. 1;

FIG. 6 is a bottom view of the writing instrument of FIG. 1; FIG. 7 is a top view of the writing instrument of FIG. 1; FIG. 8 is a perspective view of the writing instrument of FIG. 1;

FIG. 9 is a front view of the writing instrument of FIG. 8; FIG. 10 is a rear view of the writing instrument of FIG. 8; FIG. 11 is a right side view of the writing instrument of FIG. 8;

FIG. 12 is a left side view of the writing instrument of FIG. 8;

FIG. 13 is a bottom view of the writing instrument of FIG. 8; and,

FIG. 14 is a top view of the writing instrument of FIG. 8. The broken line showing of FIGS. 1-14 is for the purpose of illustrating environmental structure and forms no part of the claimed design.

1 Claim, 12 Drawing Sheets
